wood, N. J., a corporation of Delaware

Application September 5, 1930. Serial No. 479,832

6 Claims. (Cl. 60—96)

This invention relates to locomotives adapted to condense exhaust steam with the main object in view of saving water.

The invention is particularly useful in locomotives having exhaust steam operated draft appliances, and we propose to lead the exhaust steam of the locomotive engines to the draft appliance and to lead the exhaust steam of the draft appliance to a condenser or radiator of such construction and size as to have ample cooling surface to properly condense the exhaust steam of the locomotive for return to the boiler as water. We also propose to provide fan means for cooling the condenser, which fan means may be driven by exhaust steam from the draft appliance, or directly from the locomotive engine, the exhaust steam of the fan means being delivered to the condenser.

The condenser or radiator is preferably one having the condensing steam on the inside of an air current on the outside.

We further contemplate leading the condensate from the condenser into a hot well tank having means for controlling the boiler feed from the tank to the boiler.

Other objects reside in the provision of certain features of control for a locomotive of the character described.

In general we provide a construction, arrangement, and combination of parts whereby we are enabled to effectively condense the exhaust steam of the locomotive engines and accessories by compact condensing means adapted to be carried by the locomotive with ample road clearance.

A further object of the invention resides in passing the exhaust steam of the locomotive engines either serially or in parallel through the steam turbines of one or more steam turbine operated locomotive appliances and from thence into a condenser where the exhaust steam is condensed for use as locomotive feed water.

How the foregoing, together with such other objects and advantages as may hereinafter appear, or are incident to our invention, are realized, is illustrated in preferred form in the accompanying drawings, wherein—

Fig. 1 is a more or less diagrammatic side elevation of a locomotive embodying our invention.

Fig. 2 is an enlarged elevational view of the front portion of the locomotive shown in Fig. 1, certain parts being broken out to give a clear, full view of other parts, and certain parts being shown in cross section as they would appear if a cross section were taken substantially on the line 2—2 of Fig. 3.

Fig. 3 is a cross section taken substantially on the line 3—3 of Fig. 2;

Fig. 4 is a fragmentary view of a modification of the invention; and

Fig. 5 is a diagrammatic view showing the organization of the various parts of our invention in simple form.

In the drawings we have illustrated our invention embodied in a type of locomotive known as a "Shay" locomotive, although it is to be understood that the invention may be advantageously embodied in many other types of locomotives.

The locomotive herein shown comprises in general a boiler A, a fire box B, steam engines C, and suitable frame and body structure as indicated. In this particular type of locomotive the drivers are driven from the engine C by means of suitable gearing and shafting, but inasmuch as this forms no particular part of our invention and is very well known in the art, it has not been illustrated.

In accordance with our invention we equip the locomotive with a draft appliance D comprising a draft fan 4, a steam operated turbine 5 for driving the fan, and a stack 6. The turbine 5 is operated by exhaust steam from the locomotive engines, the exhaust steam being led from the engines to the turbine by means of a pipe 7.

The locomotive is equipped with a condenser or radiator E which, in this instance, is shown as extending part-way along the sides of the locomotive and across the front thereof and occupying a great portion of the height thereof, thus affording very considerable cooling surface. The condenser or radiator preferably comprises a multiplicity of finned vertically extending tubes 8 secured at their ends into tube sheets 9 which, in turn, are secured to headers. We prefer to construct the radiator in two sections, vertically considered, and provide an upper header 10 for the upper section, a lower header 11 for the lower section, and an intermediate header 12 divided into two compartments 13 and 14, the former constituting in effect a lower header for the upper section and the latter an upper header for the lower section.

The turbine 5 is provided with outlets 15 and 16 for the exhaust of steam and these outlets, as illustrated in Fig. 3, are provided with pipe connections 17 and 18 respectively for leading the exhaust steam to the condenser E. In this instance the pipe connections 17 and 18 each include a branch 19 leading to the upper header of the upper section of the condenser and a branch 20 leading to the header compartment 14.

of the lower condenser section. Thus it will be seen that the exhaust steam enters the condenser sections at the top, condenses on its way down and enters the lower headers. The condensate 5 from the header compartment 13 drains into the lower header 11 by means of pipes 21.

Air is drawn through the condenser from the outside by cooling means F comprising a pair of fans 22 and 23 mounted on a vertical shaft 24 10 and operating to draw cool air in and to expel the heated air out through the roof and down under the locomotive. These fans are driven by a steam turbine G located between the fans.

In the arrangement illustrated in Figs. 2 and 15 3 and 5 the turbine G receives its steam as exhaust steam from the locomotive engines by means of a pipe 25 leading from the engine exhaust steam pipe 7. The exhaust steam of the turbine G is led to the condenser by means of 20 pipes 27 connected with the branches 19 above mentioned. We have thus provided an arrangement in which the turbines of the cooling and draft fans are connected in parallel. High pressure steam nozzles may be provided in the turbine G to which high pressure steam may be led as 25 by means of a valve controlled pipe 28.

In order to take care of very low temperature we employ radiator covers as indicated at 31 in Figures 1 and 3 for covering a portion of the 30 radiation surfaces, thus preventing local freezing at light loads.

The condensate is led from the lower header 11 of the condenser to a hot well tank H through a pipe 32, which tank has a compartment 33 containing sponges or other means for the removal 35 of oil. A float 34 is provided in the tank for controlling the direct boiler feed from the tank to the boiler, as will now appear. A duplex pump 35 is so located that its suction is below the water 40 level in the hot well tank whereby the hot water handled by it runs to the pump cylinders by gravity, there being light suction valves employed in the pump. A second duplex pump is preferably provided as a stand-by. The water is led to the 45 pump 35 from the tank H by means of a pipe 36 and the pump delivers to the boiler check 37a through a pipe 37.

A valve 38 having an operative connection with the float 34 is provided for controlling the admission of driving fluid to the duplex pump. The 50 driving fluid is preferably steam from the turret of the locomotive which is led to the valve 38 by a pipe 40 and from the valve to the pump by a pipe 41. From the foregoing it will be seen that 55 the supply of driving fluid to the pump 35 is controlled by the float 34.

Any water lost in the system is made up by feeding water from a cold water reserve or storage tank 42 to the hot well tank as by means of a 60 valve controlled pipe 43. The pipe 43 communicably connects the tank 42 to the hot well tank H so that by opening the valve in the pipe the water level in the tank H rises. This causes the float 34 to admit steam to the feed pump thereby 65 pumping water from the tank H and in turn from the tank 42 into the boiler. In this way it is always possible to raise the water level in the boiler.

In the event that it becomes necessary to lower 70 the boiler water level, a valve 44a in a pipe 44 leading from the pipe 37 to the tank 42 is opened thus admitting water from the pump discharge to the tank 42 so that as fast as the condensed steam is returned to tank H it is pumped into the storage tank 42 instead of into the boiler. In this

way complete control of the water level is afforded.

Referring now to Fig. 4, it will be seen that we have therein shown an arrangement in which the turbines of the cooling and draft fans are connected in series. In this modification exhaust steam from the locomotive engines is led to the draft fan turbine 5 by means of the pipe 7 as before. However, the turbine G of the cooling fans receives its driving steam as exhaust steam from the turbine 5 by means of pipes 25a and 25b leading from the outlets 15 and 16 of the turbine 5 to the inlets of turbine G. The exhaust steam of the turbine G is led to the condenser by means of the pipes 27a and 27b which lead from the exhaust side of the turbine G to the branch pipes 19a of the condenser E, there being no connection in this instance from the outlets 15 and 16 of the turbine 5 to the condenser branches. In other words, all exhaust steam first passes through the turbine 5, and then through the turbine G and finally passes into the condenser.

A by-pass connection 29 is shown whereby operating steam for the turbine G may be bypassed to the condenser to control the speed of 100 the fans 22 and 23. Control is afforded by means of a valve 30 in the by-pass connection, which valve may be hand controlled or automatically controlled, as by means of a thermostat or other automatic control device diagrammatically indicated at 30a. Through the provision of the valve controlled by-pass we are enabled to by-pass steam to the condenser when the demand for steam by the turbine G is small, as would be the case in cold weather when it is not necessary to 110 cool the condenser as much as in warm weather. It is also to be noted that a valve 25c is provided in the line 25a for adjusting the amount of steam to be admitted to the turbine G. By manipulating the valves 30 and 25a any relative amount of 115 steam may be conducted to the turbine G. A similar by-pass connection may be provided in the form illustrated in Figs. 1, 2, 3, and 5, in which case, as shown in Fig. 5 for example, a by-pass pipe 29a corresponding to the pipe 29 of Fig. 4 is 120 led from the pipe 25 to the header 10 of the condenser E. A valve 30b having a thermostat 30c associated therewith and corresponding to the valve 30 and thermostat 30a of Fig. 4 is provided in the pipe 29a for affording control of the operating steam for the cooling fan turbine G.

From the foregoing it will be seen that we have provided a very compact condensing locomotive in which the exhaust steam of the locomotive engine is condensed and returned as water to the 130 boiler, the steam in its passage to the condenser operating a turbine driven draft appliance and cooling fans for cooling the condenser. The speed of the fans may be varied to accommodate varying air temperature and load on the boiler. We 135 contemplate keeping a feather of steam issuing from the condenser so as to automatically keep the feed water at approximately 212°. By this we mean that we propose to operate the condenser at atmospheric pressure, or slightly thereabove, there being no attempt in this case to produce a vacuum. The slight pressure to be maintained in the condenser is accomplished by means of a low pressure relief valve 46 of well known 140 form indicated in Fig. 3 of the drawings. However, a small exhaust steam pipe 45 may lead exhaust steam from the engine to the hot well tank to heat the water in the event of carelessness in the control of the fan speed.

We claim:—

1. In a power plant, the combination with an engine and boiler, of an exhaust draft fan for creating draft in the boiler, a steam turbine for

5 driving said exhaust draft fan, means for leading exhaust steam from the engine to said turbine to operate it, a radiator for condensing exhaust steam, fan means for cooling the radiator, a steam turbine for operating said fan means, means for leading exhaust steam from the draft fan turbine to the second mentioned turbine to operate it, means for leading exhaust steam from the second mentioned turbine to the radiator, a valve controlled by-pass for by-passing operating

10 steam around the second turbine to the radiator, and means for feeding condensate from the radiator to the boiler.

2. In a power plant, the combination with an engine and boiler of an air cooled condenser, draft creating means for the boiler, a steam turbine for operating said means, fan means for cooling said condenser, a steam turbine for operating said fan means, steam connections for passing exhaust steam from the engine through the turbines, said steam in so passing operating to drive the turbines, steam connections for passing exhaust steam from the turbines to the condenser, means for feeding condensate from the condenser to the boiler, and means associated with said condensate feeding means for affording control of the water level in the boiler.

3. In a power plant, the combination with an engine and boiler, of a condenser, fan means for creating draft in the boiler, a steam turbine for driving said fan means, fan means for cooling the condenser, a steam turbine for driving the cooling fan means, means for feeding the condensate from said condenser to the boiler, means for leading exhaust steam from the engine to the draft fan turbine for operating the same, means for leading exhaust steam from the engine to the cooling fan turbine for operating the same, means for leading exhaust steam from the draft fan turbine to the condenser, means for leading exhaust steam from the cooling fan turbine to the condenser, and means for by-passing operating steam around the cooling fan turbine to the condenser.

4. In a power plant, the combination with an engine and boiler, of a condenser, fan means for creating draft in the boiler, a steam turbine for driving said fan means, fan means for cooling

the condenser, a steam turbine for driving the cooling fan means, means for feeding the condensate from said condenser to the boiler, means for leading exhaust steam from the engine to the draft fan turbine for operating the same, means for leading exhaust steam from the engine to the cooling fan turbine for operating the same, means for leading exhaust steam from the draft fan turbine to the condenser, means for leading exhaust steam from the cooling fan turbine to the condenser, and a valve controlled by-pass for by-passing operating steam around the cooling fan turbine to the condenser.

5. In a power plant, the combination with an engine and boiler, of a condenser, fan means for creating draft in the boiler, a steam turbine for driving said fan means, fan means for cooling the condenser, a steam turbine for driving the cooling fan means, means for feeding the condensate from said condenser to the boiler, means for leading exhaust steam to the draft fan turbine for operating the same, means for leading exhaust steam to the cooling fan turbine for operating the same, means for leading exhaust steam from the draft fan turbine to the condenser, means for leading exhaust steam from the cooling fan turbine to the condenser, and valve means for controlling the supply of operating steam to the cooling fan turbine to afford control of said turbine independently of the draft fan turbine.

6. In a power plant, the combination with an engine and boiler, of a condenser, fan means for creating draft in the boiler, a steam turbine for driving said fan means, fan means for cooling the condenser, a steam turbine for driving the cooling fan means, means for feeding the condensate from said condenser to the boiler, means for leading exhaust steam to the draft fan turbine for operating the same, means for leading exhaust steam to the cooling fan turbine for operating the same, means for leading exhaust steam from the draft fan turbine to the condenser, means for leading exhaust steam from the cooling fan turbine to the condenser, valve means for controlling the supply of operating steam to the cooling fan turbine to afford control of said turbine independently of the draft fan turbine, and thermostat means for controlling said valve means.
